UNITED STATES PATENT OFFICE

GORDON E. ROEDDING, OF GRAND RAPIDS, MICHIGAN, ASSIGNOR TO GRAND RAPIDS
BRASS COMPANY, OF GRAND RAPIDS, MICHIGAN

LATCH

Application filed July 13, 1929. Serial No. 377,988.

The main object of this invention is to provide a reversible latch having few parts and these parts being simple and economical to produce and easily assembled.

5 A further object is to provide a latch in which the spring is supported so that the strain thereon is minimized, the spring for actuating the latch also being adapted to hold the latch detent yieldingly in engaging position.

10 Objects pertaining to details and economies of my invention will definitely appear from the description to follow. The invention is defined in the claims.

15 A structure which embodies the features of my invention is clearly illustrated in the accompanying drawing in which:

Fig. 1 is a fragmentary view of a door and its casing with one of my latches mounted 20 thereon, the latch casing being shown in section.

Fig. 2 is a fragmentary view looking from the left of Fig. 1.

Fig. 3 is a fragmentary view of a latch 25 mainly in section on line 3—3 of Fig. 1.

Fig. 4 is a fragmentary plan view with the casing in section, the latch being shown in keeper engaging position by full lines and in retracted or unlatched position by dotted lines.

30 Fig. 5 is a fragmentary perspective view of the bolt.

Fig. 6 is a perspective view of the bolt fulcrum member.

35 Fig. 7 is a perspective view of the bolt detent.

In the accompanying drawing 1 represents a door and 2 its casing. The body 3 of the housing is preferably a stamping. It 40 is provided with a back or base plate 4 having spaced slot-like openings 5 therein constituting catches coacting with the bolt as will be hereafter described. The rear wall 6 of the housing is provided with an opening 7 through which the bolt 8 is disposed. The front of the housing has an opening 9 therein in which the bolt swings, the bolt being provided with a hand piece 10.

45 The bolt is chambered and provided with a longitudinal slot 11 in its top wall and also

a slot-like opening 12 in its top wall spaced from the rear edge of the slot 11. A lug 13 projects from the rear edge of the slot.

The fulcrum member is provided with a downwardly projecting lug 17 opposite the flange 15. This lug is headed or upset at 18. The fulcrum member is provided with a pair of laterally projecting arms 19 having rounded terminal portions 20 in bearing engagement with the rear wall of the housing which in the embodiment illustrated constitutes an abutment therefor. The bolt is thus supported for pivotal or swinging and longitudinal tilting movement.

55 The detent member 21 is also a sheet metal stamping and has an opening 22 therein engaged with the stud or lug 23 projecting upwardly from the base plate within the chamber of the bolt so that the detent is supported for swinging movement with the bolt and limited tilting movement independently thereof. This detent member 21 is provided with a T-shaped arm 24 at its forward end projecting through the slot of the bolt with the parts 25 overhanging the bolt so that, 60 when the bolt is tilted longitudinally, the detent is actuated to disengage its lugs 26 from the slot 5.

65 The detent is actuated by means of the coiled spring 27 one end of which engages 70 and is supported by the arm 24. The other end of the spring engages over the lug 13 on the bolt and is in thrust engagement with the fulcrum member, thereby applying yielding pressure thereto and acting to yieldingly hold the bolt in its keeper engaging or central position shown in Fig. 1.

75 The keeper 28 is preferably provided with a trip or tappet 29 adapted to engage the projecting end of the bolt when the door is 80 swung to closed position, thereby disengaging the detent and permitting the spring 27 to throw the bolt into engagement with the keeper 28. Where the trip or tappet 29 is 85 not present the detent may be released by an inward pressure on the hand piece 10 of the bolt which tilts the bolt sufficiently to disengage the detent allowing the spring to actuate the bolt.

I have illustrated an embodiment or adaptation of my invention well adapted for use on refrigerators. I have not attempted to illustrate or describe other embodiments or adaptations as it is believed that this disclosure will enable those skilled in the art to which my invention relates to embody or adapt the same as may be desired.

Having thus described my invention what I claim as new and desire to secure by Letters Patent is:

1. In a latch, the combination with a housing provided with a back plate, a chambered bolt having a slot in its top wall and an opening in its top wall spaced from the rear edge of the slot, said bolt having a forwardly projecting lug at the rear edge of the slot, a fulcrum member having a downturned flange at its forward edge engaged in said slot of said bolt and perforated to receive said lug thereon and a downturned lug engaged in said opening in said bolt, said fulcrum member having laterally projecting arms engaging said housing, a thrust member disposed within said bolt and pivotally mounted on said base plate and having an arm at its forward end projecting through said slot in said bolt, and a spring disposed between said arm on said thrust member and said flange on said fulcrum member.

2. In a latch, the combination with a housing provided with a back plate having spaced detent catches, a chambered bolt having a slot in its top wall and provided with a fulcrum abutting said housing, a detent member disposed within said bolt and pivotally and tiltably mounted on said base plate and having an upwardly projecting T-shaped arm on its forward end projecting through said slot in said bolt, said detent member being provided with a lug engageable with said catch on said base plate, and a spring disposed within said bolt to engage said arm on said detent and acting to urge the fulcrum of the bolt against its supporting abutment on the housing.

3. In a latch, the combination with a housing, a chambered bolt provided with spaced fulcrums within said housing, a detent member disposed within said bolt mounted on said plate to swing with the bolt and for tilting movement independent of the bolt, said housing having a catch for said detent, and a spring interposed between said detent and said bolt.

4. In a latch, the combination with the housing, of a bolt mounted for swinging and tilting movement, a detent member mounted upon said housing for tilting swinging movement and operatively associated with said bolt to swing therewith but having tilting movement independent of said bolt, said housing being provided with a detent catch disposed to coact with said detent, and a spring for actuating said detent to engaging

position, said bolt constituting means for releasing said detent.

In witness whereof I have hereunto set my hand.

GORDON E. ROEDDING.
